UNITED STATES PATENT OFFICE.

JEAN BAPTISTE DANDOIS, OF BRUSSELS, BELGIUM.

LOCKING DEVICE FOR SLIDING WINDOWS.

Application filed February 25, 1922. Serial No. 539,061.

To all whom it may concern:

Be it known that I, JEAN BAPTISTE DANDOIS, a subject of the King of Belgium, 5 Rue de la Riviere, Brussels, Belgium, have invented new and useful Improvements in or Relating to Locking Devices for Sliding Windows, of which the following is a specification.

This invention relates to locking devices for sliding windows, and more particularly frameless windows, and the principal object thereof is to provide a locking device which will ensure a perfect locking of the glass without the risk of breaking it, by applying resilient pressure longitudinally on the lateral edges of the glass throughout the whole of its height, and transversely throughout the whole width, in any position of the glass.

A further object of the invention is to render possible a free release of the glass even when the packing of its guides is in a wet or dirty condition.

A further object of the invention is to provide a construction which may be easily and quickly mounted on any car whatever be the dimensions of the glass.

A still further object of the invention is to make possible the immediate removal of the mechanism for the purposes of examination and adjustment and for replacing the glass without necessitating the dismantling of any parts of the door, or interference with the packing or with the lower panel of the said door.

To these ends the locking device according to this invention comprises a frame of the same width as the glass, constituted by two uprights rigidly connected together at their centres by a cross-bar on which is mounted a central mechanism with opposite horizontal sliding rods terminating each in a slide block or shoe engaging with a horizontal guide bracket secured to the upright of the door, the guide of the said support being curved from the interior towards the exterior of the door.

Owing to the said curving of the guides, the slide blocks or shoes, the mechanism to which they are secured, and the central cross-bar of the frame carrying the said mechanism, as well as the uprights of the said frame, may be moved towards, or away from, the plane of the ledges of the door by which the glass is guided, that is to say forced to jam the said glass against the said ledges or to release it.

A construction of locking device according to the invention is illustrated by way of example in the accompanying drawing in which Figure 1 is an elevation of the inner face of a door provided with the locking device released in the half-lowered position of the glass.

Figure 2 is an elevation of the mechanism with a handle placed on the cross-bar of the movable frame, which by means of its uprights and its cross-bar, exercises a longitudinal and transverse pressure on the glass.

Figure 3 is a view similar to the preceding one, showing the sliding rods with the slide block or shoe of the said mechanism.

Figure 4 shows in plan the same rods, the shoes of which engage with bent or curved guides secured to each upright of the door, and,

Figure 5 is a plan of the fitting carrying the mechanism with a handle.

The window locking device is constituted by a movable frame, the uprights *a* of which, connected together by a central cross-bar *b*, are suspended loosely by means of fittings *c*, *c*, on screw-threaded rods or bolts *d*, *d*, secured to the upper cross-bar *e* of the door. A resilient washer *f*, preferably of rubber, is placed on each screw spindle *d* between the head and the fitting *c*. Another washer *g* is provided on each screw-threaded rod or bolt between the fitting *c* and the cross-bar *e*. The space comprised between each upright *a* of the adjustable frame and a corresponding ledge *h* provided on each upright *i* of the door, forms a guide for the lateral edge of the glass window, *y*.

In the middle of the central cross bar *b* is secured the bracket *j* with a disc *k* having a handle *l*, the said disc being rotatable about the pivot pin *m* of the bracket *j*. The disc *k* is provided with two eccentric slots *n* *n* in which may slide the projections or fingers *o*, *o*, of the two nuts *p* *p* of two screw-threaded rods *q*' *q*' each of which is guided in a bracket *r* secured to the cross-bar *b*.

The fingers *o*, *o*, are moreover guided in two horizontal rectilinear guides *s*, *s*, of the bracket *j*.

Each rod *q* terminates in a sliding shoe or block *t* which is provided at the bottom with an oblique guide slot *u* for guiding the said block on the free end *v* of an arm *w* secured to the upright *i* of the door. This arm is horizontal, but its free end is bent towards the outside of the door.

The handle l can be brought into the two end positions l' , l'' , where it is automatically locked by engaging with the notches x^1 , x^2 , of its guide z in the bracket j (Figure 5).

5 The working of the device described is as follows:

By bringing the handle into the position l' , the rods q are pulled and moved towards each other owing to the action of the slots n 10 of the disc k on the projections or fingers e of the nuts p of the rods q . The blocks or shoes on the ends of the said rods, slide on the arms w and move nearer to the plane of the ledges h of the door, owing to which 15 the adjustable frame is moved nearer to the said ledges h and the glass y is pressed against the said ledges.

If on the contrary the handle l is brought into the position l'' the reverse movement 20 of the rods q and the block or shoes t will take place, so that they will be moved away from the plane of the ledges h and will move the adjustable frame away from the plane of the said ledges so as to release the 25 glass y .

It must be understood that owing to the rubber washers f inserted between the fittings e and the screw heads d , the pressure 30 of the adjustable frame against the upper part of the glass y will be a resilient one, since when pressed against the said glass, the adjustable frame will bear on the said washers. The washers g , form stops for 35 deadening the shock of the glass when it is fully raised.

The regulation of the degree of pressure of the adjustable frame against the glass is effected by simultaneously tightening or 40 loosening the nuts p on the rods q , and by tightening or loosening the screws d owing to the resiliency of the washers g .

Having now particularly described and ascertained the nature of my said invention

and in what manner the same is to be performed, I declare that what I claim is:— 45

1. A glass-locking device comprising an adjustable frame opposite the door ledges guiding the glass, characterized by the said frame being freely suspended, with the insertion of resilient washers, on the stems of 50 two bolts secured to the upper cross-bar of the door, and by a mechanism with a handle, mounted on a central cross-bar of the said adjustable frame, bringing closer together or moving farther apart two oppositely arranged horizontal rods terminating each in a block or shoe forming a slide block on the bent or curved end of a horizontal arm secured to the upright of the door, the movement of the said slide blocks on the ends of 55 the arms simultaneously bringing them nearer to, or farther away from the plane of the ledges of the glass, that is to say moving the frame nearer to or further away from the said ledges, so that the glass is 60 locked or released.

2. In the device such as set forth in claim 1, a mechanism with a handle for bringing the rods with slide-blocks or shoes nearer together or further apart, which mechanism 70 is characterized by a bracket-support provided with a pivot pin on which swings a disc with a handle, provided with two eccentric slots, in each of which engages the projection or finger of a nut screwed on the 75 rods with slide-blocks, the said projection being guided in horizontal guides with which the bracket-support is pivoted, said support having a guide for the handle of the disc.

80 In witness whereof I affix my signature.

JEAN BAPTISTE DANDOIS.
